UNITED STATES PATENT OFFICE

163,557

SWEATER

Hermina Balyer, Cleveland, Ohio

Application February 17, 1951, Serial No. 14,255

Term of patent 7 years

(Cl. D3—4)

To all whom it may concern:

Be it known that I, Hermina Balyer, a citizen of the United States, residing in the city of Cleveland, county of Cuyahoga, and State of Ohio, have invented a new, original, and ornamental Design for a Sweater, of which the following is a specification, reference being had to the accompanying drawing, forming a part thereof.

Figure 1 is a front elevation of a sweater showing my new design; and Figure 2 is a front elevation showing the two tabs folded back; and Figure 3 is a back view of the same.

I claim:

The ornamental design for a sweater, substantially as shown.

HERMINA BALYER.
